UNITED STATES PATENT OFFICE

LAWRENCE A. WILSON, OF PITTSBURGH, PENNSYLVANIA, ASSIGNOR OF ONE-HALF
TO HERMAN C. H. WEIDNER, OF PITTSBURGH, PENNSYLVANIA

AUTOMATIC CLOSING DEVICE FOR CARTONS AND THE LIKE

Application filed June 25, 1927. Serial No. 201,450.

This invention relates to a closing device for cartons, milk bottles and the like, the general object of the invention being to provide a flat part on the closure, with means for automatically holding it in closed position so that the contents of the container will be protected from dirt, insects and the like when the device is used on a milk bottle, for instance, and when used on a carton for cigarettes, for instance, the cigarettes will be protected from the drying effect of the atmosphere, and in this case the device also acts to hold the carton in its original shape.

5 This invention also consists in certain other features of construction and in the combination and arrangement of the several parts, to be hereinafter fully described, illustrated in the accompanying drawings and specifically pointed out in the appended claim.

10 20 In describing my invention in detail, reference will be had to the accompanying drawings wherein like characters denote like or corresponding parts throughout the several views, and in which:—

25 Figure 1 is a view of a cigarette carton, showing the invention thereon.

Figure 2 is a similar view, but showing the flap in open position.

Figure 3 is a vertical sectional view through 30 the upper part of Figure 2.

Figure 4 is a bottom plan view of the device itself.

Figure 5 is a view similar to Figure 3, but showing a slight modification.

35 Figure 6 is a view of another modification.

Figure 7 is a view of the device shown in Figure 6.

As shown in these views, the device comprises a strip 1 of cardboard or the like which has a flap 2 at one end thereof which is hingedly connected with the strip, such as by a scored line or a weakened line. The flap is normally held in alignment with the strip by a rubber or other resilient band 3. This 45 device may be pasted or otherwise fastened

to the top of a carton A of cigarettes or the like, as shown in Figures 1, 2 and 3, so that by tearing away the top of the carton under the flap, the flap can be used to close the open end of the carton, as clearly shown in these 50 figures. When a cigarette is to be removed, it is simply necessary to raise the flap, take out the cigarette and release the flap so that the strip 3 can return the flap to closed position.

55 Figure 5 shows the device placed under the top of the carton A' instead of being fastened to the upper face of the top part. In this case, the device is placed on top of the cigarettes and then the carton is folded over the 60 same.

Figures 6 and 7 show the same arrangement, but in this case, the strip 1' is provided with a metal clip 4 which is formed with a tongue 5 which is adapted to be passed 65 through the folded top of the carton A'' which not only helps to hold the top closed but also attaches the device to the carton.

From the foregoing it will be seen that this device will not only keep the carton 70 closed automatically, thus protecting the cigarettes from the drying action of the atmosphere, but it also tends to hold the carton in its proper shape.

75 It will also be understood that while the device is shown in use on a carton of cigarettes, it can be used for closing other containers. It can also be used for a milk bottle closure by making it of disk shape to fit the mouth of the bottle.

80 It is thought from the foregoing description that the advantages and novel features of my invention will be readily apparent.

I desire it to be understood that I may make changes in the construction and in the 85 combination and arrangement of the several parts, provided that such changes fall within the scope of the appended claim.

What I claim is:—
A closure device for a package of cigarettes 90

comprising a flat strip of cardboard having a transversely arranged scored line adjacent one end thereof for hingedly connecting said end to the strip, a resilient band fastened to the under side of the strip and extending over the hinged end for normally holding said end in alignment with the strip and means for fastening the strip to the top of a package of cigarettes with the hinged end over an opening formed in one end of the top of the package.

In testimony whereof I affix my signature.

LAWRENCE A. WILSON.
